UNITED STATES PATENT OFFICE.

NEWTON K. BILLOW, OF COLUMBUS, OHIO.

PILLOW.

1,208,277.

Specification of Letters Patent. Patented Dec. 12, 1916.

Application filed May 15, 1915. Serial No. 28,451.

To all whom it may concern:

Be it known that I, NEWTON K. BILLOW, a citizen of the United States, residing at Columbus, in the county of Franklin and State 5 of Ohio, have invented a certain new and useful Improvement in Pillows, of which the following is a specification.

The body of a pillow as commonly constructed includes a collection of feathers 10 completely inclosed in a ticking, the ticking being stitched. Ticking to prevent the protrusion and escape of the feathers is a tightly woven, tough fabric akin to canvas and like canvas is difficultly pervious to water. It 15 is impracticable to wash feathers while in a ticking. After some use the feathers of a pillow become somewhat compacted and yield an offensive odor. To wash such a pillow it is the practice to cut the stitches 20 of the ticking, remove the feathers and wash separately the ticking and the feathers. Loose feathers are difficult to handle and are likely to scatter and be blown about.

The object of the present invention is to 25 provide a construction of pillow in which the feathers can be washed without removing them from their immediate container and without removal or destruction of the immediate container and the invention is 30 embodied in the construction hereinafter described and then claimed.

In the drawing herewith—Figure 1 is a 35 side view of the pillow. Fig. 2 is a longitudinal section.

In the views 1 designates the feathers, 2 a 40 sack or cover that immediately incloses and contains them and 3 the ticking.

The sack is made of coarsely woven material freely pervious to water but sufficiently closely woven to prevent the escape 45 of the feathers, said sack being shown as of

the usual oblong form and stitched at its edges to permanently inclose the feathers. The fabric of this sack or container is of a stout loosely woven material—coarse muslin 45 for example—(not a netting) and such as will permit the sack while containing the feathers to withstand the rough laundrying process in the manner usual to ordinary heavy garments and at the same time prevent 50 the escape of the feathers therefrom. When so laundried the water, saponified or otherwise, freely passes through the sack and feathers, thoroughly cleaning them. The pillow may be hung upon the line and 55 dried as usual with ordinary laundry and upon drying the feathers will be found relieved of their offensive odor and to be light and fluffy.

Because of the inner sack inclosing the 60 feathers it is not necessary to employ the usual sewed ticking. On the contrary it is expeditious and convenient to employ a ticking of pocket form and having an open end provided with a flap 3^a so that the sack 65 2 can be easily inserted and removed. The flap 3^a is sewed at its ends to the edge of the ticking to insure its lying flat upon the body of the ticking and thus not making a lump when the ticking with its contents are 70 inserted into the usual pillow slip.

What I claim is—

As an article of manufacture, a washable pillow consisting of a sack of loosely woven fabric adapted to permit the free passage 75 of water therethrough, and a filling of pillow feathers in said sack, said sack being permanently closed whereby the pillow including its feathers may be washed without removing them from the sack.

NEWTON K. BILLOW.
